UNITED STATES PATENT OFFICE.

WALTER LARKIN, OF PHILADELPHIA, PENNSYLVANIA, ASSIGNOR TO H. BRINTON COMPANY, OF PHILADELPHIA, PENNSYLVANIA, A CORPORATION OF PENNSYLVANIA.

STOP-MOTION.

1,269,464.

Specification of Letters Patent. Patented June 11, 1918.

Application filed November 2, 1916. Serial No. 129,127.

To all whom it may concern:

Be it known that I, WALTER LARKIN, a citizen of the United States, residing in Philadelphia, Pennsylvania, have invented 5 Stop-Motions, of which the following is a specification.

One object of my invention is to provide a knitting machine with a stop motion which in addition to being materially simpler than 10 those commonly employed to attain the same ends, shall be of such a nature as to be reset more quickly and with greater ease than would ordinarily be possible.

Another object of the invention is to provide a stop motion in which the member for releasing the belt shifting or other controlling mechanism shall be operated directly by the pull of the end of the yarn;—the arrangement of parts being such that the device 20 controlled by a lack of continuity of the thread shall be so coupled to the mechanism which is operated by a knot in the yarn, that either of them shall be capable of actuating said releasing member.

25 A further object of the invention is to provide a stop motion having the above characteristics which in addition shall have its parts so disposed that the knot actuated mechanism shall be operated without any 30 jerking action by a comparatively gentle pull on the arm or sweep over which the yarn passes.

These objects and other advantageous ends I secure as hereinafter set forth, reference 35 being had to the accompanying drawings, in which,

Figure 1 is a side elevation of a stop motion constructed according to my invention;

Fig. 2 is a front elevation of the upper 40 portion of the structure shown in Fig. 1;

Fig. 3 is a perspective view illustrating the construction of the thread-and knot-controlled members at their point of junction;

Fig. 4 is a full sized plan showing the 45 relation between my invention and certain other parts of a knitting machine;

Fig. 5 is a perspective view of the sweeps and certain of their associated parts;

Fig. 6 is a plan, partly in section, further 50 illustrating the construction of the sweep-actuated mechanism;

Fig. 7 is a vertical section on the line 7—7, Fig. 6; and

Fig. 8 is a side elevation illustrating the 55 construction of certain parts of the machine.

In the above drawings 1 represents a supporting casting designed to be attached to the frame of a circular knitting machine provided with fast and loose pulleys 2 and 3 mounted on a driving shaft 4. The position of a driving belt on these pulleys is governed by a belt shifter 5 slidably mounted on a guide bar 6 and tending at all times to move under the action of a spring 7 mounted on said bar, to change the belt from 60 the first to the second of said pulleys. This shifter is operatively connected through a link 8 to a manually controlled lever 9 and said link is so formed that when this lever is turned to the position shown, said shifter is 70 retained in place against the action of the spring 7. The lever 9 is acted on by one arm of a lever 9^a whose second arm is engaged by an arm 10^a of a lever 10 suitably pivoted to the frame. Said latter lever also 75 has an arm 11 which is formed to engage a suitable retaining shoulder of a lever 12.

Said lever 12 has two other arms 13 and 14, of which the first is connected to one end of a spring 15 designed to retain it in holding engagement with the arm 11 of the lever 10. The same arm 13 is connected through a link 16 to an arm 17 forming part of a collar 19 fixed by a set screw 20 to a transversely extending shaft or spindle 18 journaled in the bearings carried by or forming part of the structure 1. The outer end of this collar is slotted for the reception of a lever 21, which is pivotally mounted therein and has connected to one of its free ends a 90 rod 22 whose opposite end is slidably supported by an arm 23 fixed to and projecting from a vertically guided, rotatable spindle 24.

The second end of the lever 21 has ad- 95 justably mounted on its outer or second free end a longitudinally movable plate 25 which, when said lever is turned on its supporting pivot, is brought into the path of a series of teeth 26 which project radially from a 100 flange or collar 27 forming part of or attached to the fast pulley 2.

The supporting plate 1 has fixed to and projecting vertically up from it a standard in the shape of two rods 28 and 29, of which 105 the latter carries a casing 30 about midway between its top and bottom and braced to the rod 28 by a transverse member 31. Similarly the upper ends of the two rods are braced together by a second horizontal 110

member 32 and on the top of the member 29 is carried a second casing 33.

Projecting downwardly from the under side of the plate 1 is a fulcrum post 34 to which is pivoted a bell crank lever 35, whose lower end is slotted for the reception of an arm 36 rigidly connected to and projecting at right angles from the rod 22. The second end of this bell crank lever is connected 10 through a tension member in the shape of a wire 37 with a disk 60 which is vertically slidable upon a screw 61 threaded into the top of the rod 29 and serving to retain in place the cover 62 of the casing 33. Said disk has fixed to it in any desired manner a block or lug 64 to which the upper end of the wire 37 is clamped by means of a screw 63, so that any upward movement of the disk naturally likewise draws the wire upwardly. 20

The casing 33 is made up not only of the cover 62 but also of a flanged collar 65 fixed to the top of the rod 29 and recessed in its top face to form a chamber into which the stems 38 of a pair of sweeps 40 extend through upwardly opening slots 68, the whole being so arranged as to prevent access of lint, dirt, etc., to the parts hereafter described, which are inclosed by said casing. 25 This flanged collar has threaded into it one end of the top bracing member 32 which extends through the vertically slotted end of the rod 28 where it is clamped with its associated parts so as to be held from turning 30 by a screw 66 threaded into the vertical walls of the slot;—the upper end of said rod being prevented from spreading when the screw is set up by means of a ferrule or collar 67 extending around them. 35

40 The top bracing member 32 extends beyond the rod 28 for a distance equal in the present case, to the distance between the two rods 28 and 29, and at its outer end non-rotatably carries a transverse plate 39 whose extremities are turned at right angles to its general plane and are then extended 45 up and over to form downwardly opening bearings for the reception of the stems 38 which also rest upon the top edges of said 50 plate 39. It is noted that said stems 38 pass through the slots 68 in the flange of the collar 65 of the casing 33 so as to be easily removable therefrom, and owing to the construction of the plate 39 with its bearing 55 lugs 69, the inner end of either stem may, after removal from the slot 68, be swung downwardly and then toward the brace 32 so as to free its outer end from the plate and permit of its complete removal. 60

60 The ends of the stems projecting inside the casing 33 are turned at right angles to their general line and given a helical form as indicated at 70, so that they each have a projecting end or finger extending under 65 the disk 60. Each of these ends is engaged

by a spring 71 which is fixed to a collar 72 upon the rod 29 so that the sweeps 40 are normally retained in an elevated position at an angle of about 45° to the horizontal. When, however, either of said sweeps is 70 drawn downwardly so as to cause its stem 38 to turn in its bearings, its projecting arm or finger 70 engages the under side of the plate 60 so as to raise the same and thereby draw the wire 37 upwardly. 75

To facilitate the placing of the stems of the sweeps in place, the flanged edge of the collar 65 is preferably slotted as indicated at 76 to permit of the convenient introduction of the coiled or otherwise formed end 80 of said stem. The outer extremity of each of the sweeps is first bent at right angles to its general line and then again bent so as to extend for a short distance parallel with said line, after which it turns abruptly 85 through an angle of 180° and is returned in engagement and parallel with itself to the point at which it was first bent. Beyond this its extremity is curved over and down toward its two parallel portions to form 90 a retaining loop which will hold the yarn as long as the sweep extends in a line above the horizontal. Thereafter the yarn is free to be drawn out of this finger or holder 41. 95

The rotary member 24 extends upwardly through the supporting plate 1 and enters the intermediate casing 30, where through suitable mechanism, forming no part of this invention though well known to the art, it is connected to horizontal spindles 42. 100 These latter are extended from the casing through suitable bearings carried by the lower part of a horizontally slotted plate 43 which in turn is supported by arms 44 rigidly fixed to and projecting radially from 105 said casing. Each of the rotating spindles 42 has a series of yarn controlled fingers 45 projecting from it and designed to cooperate with the slotted plate 43 in the manner well known to the art, so as to be released in the absence of the yarn and fall to an approximately horizontal position, thereby giving a partial rotation to its spindle 42. Thereupon the mechanism within the 110 casing 30 releases the rotary spindle 24, permitting it a partial revolution in the direction of the arrow, Fig. 3. The particular means for causing such action of the spindle 24 is immaterial, since obviously any suitable device may be employed for this 115 purpose without departing from my invention. 120

Each of the arms 44 carries under the above described end detector a knot catcher in the shape of a circular plate 46 having 125 a number of perforations adjacent its periphery through which the yarn passes to the detector.

Under normal conditions the yarn extends from suitably supported bobbins through 130

one of the perforations of the yarn catcher, thence between the yarn fingers 45 and the slotted plate 43 of the detector;—it being understood that the arrangement is such 5 that the yarn alone serves to prevent said fingers falling from a vertical to a horizontal position. The yarn passes then through a guide 47 on the top of the plate 43, through the loop 41 of the sweep and thence down to the knitting machine.

10 In putting the machine in operation the projecting arm of the lever 10 is forcibly raised against the action of a spring 10^a, thus drawing the arm 11 back of the shoulder on the lever 12. The lever 9 is then turned to carry the attached end of the link 8 over and behind the pivotal point of said lever, where it is retained against the action of the spring 7, this operation 15 of said lever also moving the shifter 5 into position to bring the driving belt on to the fast pulley 2. Under the action of gravity on the various parts, the end 25 of the lever 21 is normally held in the position shown in Fig. 4 to one side of the plane of revolution of the teeth of the flange or wheel 27.

With these conditions, it is now possible 30 to operate the knitting machine in the well known manner, although if at any time the end of either thread passes through and out of the yarn fingers 45 these are permitted to drop, so actuating or releasing the mechanism in the casing 30 as to cause a partial 35 revolution of the vertical spindle 24 in the direction of the arrow, Fig. 3, whereupon the arm 23 engages a stop 50 on the link or rod 22, which swings the lever 21 on its pivot so as to turn its end portion 25 into the 40 path of the teeth 26. Since the wheel carrying these teeth is rotating with the fast pulley 2, one of said teeth immediately engages said lever, causing it to turn the spindle 18 and with it the arm 17, which 45 then acts through the link 16 to swing up the arm 13 and moves the arm 12 downwardly against the action of the spring 15. This at once releases the lever arm 11 and causes the arm 10^a of the lever 10 to act on 50 the lever 9^a so as to turn the lever 9 and release the belt shifter 5, which under the action of the spring 7, moves to transfer the belt from the fast pulley 2 to the loose pulley 3. Power is thus cut off from the 55 machine, which is quickly stopped by an automatic brake connected with the lever 10 but forming no part of the present invention.

Similarly when a knot or enlargement of 60 the yarn reaches the plate 46 and is held thereby, or whenever there is an abnormal tension from any cause, the increased tension of said yarn draws down the sweep 40 and rotates its stem 38 thus causing the arm 65 or coiled end 70 to act upon and raise the

disk 60. The tension wire 37 is thereupon drawn up, swinging the bell crank lever 35 on its pivot and through the arm 36, longitudinally moving the link 22. As before such movement causes the plate 25 to be 70 brought into the path of the teeth 26 and the resulting engagement of said plate or arm by one of the teeth at once results in the cutting off of power and stoppage of the machine. Obviously, even if the machine 75 should continue to knit after the sweep had been drawn down to the horizontal the yarn would be disengaged from the loop 41 without breakage so that after the knot has been removed from the plate 46, it is merely necessary to replace it in its loop 41, whereupon the machine may be again put in operation.

From the above description it will be noted that by my invention the effect of abnormal tension in causing stoppage of the machine is comparatively gradual and occurs without any jerk or serious tension upon the yarn so that there is no breakage. Moreover the device as a whole is comparatively 90 simple, since both the knot catching and the end detecting devices are operative upon the same main connecting lever 21 whereby the power of the machine is caused to release the belt shifting mechanism.

With such an arrangement of parts it is a relatively simple and quickly performed operation to put the machine in operation after it has been stopped by the action of the above described apparatus, since if the appearance of an end of the yarn has released one of the detector fingers, the splicing of the yarn and its reengagement with the fingers 45 and plate 43, will again put the machine in condition for operation;—it 100 being understood that the mechanism in the casing 30 is set by a partial revolution of a setting arm 56 on the rod 24 after the yarn finger 45 has been raised to the yarn-engaging position.

It is moreover noted that a relatively small downward movement of the sweep 40 under a comparatively gentle pull exerted upon the yarn will shift the lever 21 into position to cause stoppage of the machine, regardless of whether this is due to the operation of the knot catcher or whether it is caused by increased tension from imperfect winding of the bobbins or other cause.

I claim:—

1. The combination in a knitting machine of a rotatably supported shaft; machine-stopping means connected to the shaft and actuated by the rotary movement thereof; a source of power for turning the shaft including a rotary member normally disconnected therefrom; a lever fulcrummed on the shaft and movable into and out of position to cause rotary movement to be imparted thereto from said member; a link 125

120

125

130

connected to the lever; two abutments on the link; two arms respectively operative on the abutments to move the link longitudinally; and two independent yarn controlled devices 5 respectively connected to said arms for actuating the same to move the link.

2. The combination in a knitting machine of a supporting structure having a casing; a spindle extending into said casing; 10 a bearing carried by the structure and engaging opposite sides of said spindle; an arm on the spindle within the casing; a sweep arm also connected to the spindle; a member within the casing operated on by 15 the first arm to cause stoppage of the machine; and a bearing on the structure removably engaging said spindle adjacent the sweep arm.

3. The combination in a knitting machine 20 of a supporting structure; a plate mounted thereon and having two unaligned portions formed to constitute a bearing engaging op-

posite parts of a spindle; a second spindle bearing; a spindle removably mounted in said bearings; a sweep arm and an operating 25 arm for said spindle; with means controlled by said operating arm for stopping the machine.

4. The combination in a knitting machine of a supporting structure; a knot catching 30 plate thereon; a casing having a cover and also mounted on said structure; a plate vertically guided in the casing; a wire connected to said plate and extending longitudinally of the supporting structure; a 35 spindle having one end extended into the casing and having an arm projecting under said plate; a sweep arm on the other end of the spindle; a bearing supporting said spindle adjacent the sweep arm; and a 40 spring operative on the arm within the casing to normally maintain the sweep arm in elevated position.

WALTER LARKIN.
